UNITED STATES PATENT OFFICE.

FREDERICK C. LAVARACK, OF MONTCLAIR, NEW JERSEY.

RAIL BOND.

Application filed April 4, 1922. Serial No. 549,437.

To all whom it may concern:

Be it known that I, FREDERICK C. LAVARACK, a subject of the King of Great Britain, and a resident of Montclair, in the 5 county of Essex and State of New Jersey, have invented a new and useful Rail Bond, of which the following is a specification.

This invention relates to railway signalling track circuit rail bonds.

10 The primary object of this invention is the production of a form of bond which will not be likely to break at a point adjacent the web of the rail.

15 A further object of the invention is the production of a bond which is so stiff that it will remain substantially as placed and will not require the use of devices known as bond wire protectors to keep it in place.

20 Other objects and advantages will appear 25 as the description of the particular physical embodiment selected to illustrate the invention progresses, and the novel features of the invention will be particularly pointed out in the appended claim.

25 In describing the invention in detail, and the particular physical embodiment selected to illustrate the invention, reference is had to the accompanying drawings, wherein I have illustrated a particular preferred 30 physical embodiment of my invention and wherein like characters of reference designate corresponding parts throughout the several views, and in which:

35 Fig. 1 is a top plan view of my improved rail bond in place connecting two rails, with certain parts broken away to more clearly show the construction: Fig. 2 is a vertical sectional view on the plane indicated by the line II—II of Fig. 1, viewed in the direction of the arrows: Fig. 3, is a fragmentary horizontal sectional view on the plane indicated by the line III—III, Fig. 2.

40 4 designates the abutting ends of two rails, which are to be joined by an electrical conductor so that they will be at all times electrically continuous it being found that reliance cannot be placed on the mere contact of the rails.

45 It has been customary to bore two holes 50 in the web of each rail and use two bond wires each end of each wire being held to the webs by a single grooved channel pin. By this method of construction it is necessary to bore four holes. The single unconnected wires are so flexible that it is necessary to use bond wire protectors to keep

them in place so that they will not get upon the ball of the rail and be cut by a passing train or trip a track walker.

55 A more improved method is to use a duplex or two grooved channel pin as shown in the patent to F. C. Lavarack, dated May 19, 1914, Number 1,097,340. This method also makes use of two wires although the necessity for boring four holes is avoided 60 as two are sufficient, one in the end of each rail.

65 The difficulty experienced with the first mentioned construction which is also present in the Lavarack construction is that the bond wires often break at the point where they rest against the sharp edge of the hole in the web of the rail. This breakage probably arises from the fact that the point of contact between the sharp corner of the hole 70 in the rail and the bond wire is a point for some reason extremely susceptible to corrosion and the bond wire does frequently corrode at this point thus weakening it at this particular point. Another reason the 75 bond wire is weak at this point is that it frequently gets nicked which not only weakens it but allows the hereinbefore mentioned corrosion to more easily and rapidly take place just at this particular point. 80 Another cause for the breakage at this particular point is the vibration of the bond wire due to shaking and jarring of the track by passing trains. The point of oscillation is at the point of contact of the 85 bond wire and the sharp edge of the hole in the web of the rail. If the bond wire has been weakened by nicking or by corrosion or by both then the vibration on this point soon breaks the bond wire. Even if the bond wire has not been nicked or corroded the continued vibrating of the bond wire against the sharp edge of the hole in the web is very destructive of the bond wire 90 and shortens its effective life materially.

95 In the present construction one hole only is bored in the web of each rail and a duplex channel pin is used to hold the ends of two bond wires in contact with the rail. The duplex pins are designated by 5 in the drawing and the two bond wires by 100 6 and 7. 105

110 In my improved construction, however, the two bond wires are tightly twisted throughout their entire length except for the short ends which are in contact with the channel pin and rail. The result of this

construction is that the bond wires are held from vibration on the sharp corners 8 and 9 of the web of the rail and are held tightly against the channel pin which, as usual, is thoroughly tinned and the sharp edges thereby destroyed. By this construction the vibration is transferred from a weak point, that is, the point of contact of the bond with the edge of the hole in the web, to a point of normal strength where no extreme-
ly sharp corners to vibrate against exist.

From the foregoing description taken in connection with the drawings it will be understood that I have constructed a device for the purpose specified in which a channel pin is provided having diametrically opposite grooves or channels therein and that the end of a wire resting in one groove is balanced by the end of another wire in the diametrically opposite groove, so that due to the twisting of the wires both are held tightly against the channel pin. To get this result I have made the number of wires even.

As rails are generally about thirty feet long and as there are some two hundred and fifty thousand miles of railroad in the United States alone, it is readily seen that if all of the mileage were bonded the number of breakages would be enormous and

the resulting expense very great because when a rail bond breaks it is necessary to bore new holes as the old holes are not suitable for re-use. Applicant's invention is one of great comparative utility in the domain of railway signalling.

Although I have particularly described the construction of one physical embodiment of my invention, and explained the principle thereof, nevertheless, I desire to have it understood that the form selected is merely illustrative, but does not exhaust the possible physical embodiment of the idea of means underlying my invention.

What I claim as new and desire to secure by Letters Patent of the United States, is:

A bond for the abutting ends of two rails, each provided with an orifice, comprising channel pins, fitting within said orifices, and having diametrically opposite grooves, a pair of bonding wires having their ends seated in said grooves and twisted together throughout the remainder of their length to form a rigid reinforced bonding member, the twisted portions adjacent the ends causing the separated end portions to draw toward each other into the bottom of the grooves.

FREDERICK C. LAVARACK.
